[57] CLAIM

The ornamental design for a food serving bowl, as shown and described.

DESCRIPTION

FIG. 1 is a top plan view of a food serving bowl showing our new design;

FIG. 2 is a bottom plan view;

FIG. 3 is a side elevational view;

FIG. 4 is an elevational view of the side opposite that shown in FIG. 3;

FIG. 5 is an end elevational view;

FIG. 6 is an elevational view of the end opposite that shown in FIG. 5;

FIG. 7 is a top plan view of a food serving bowl showing a modification of our new design;

FIG. 8 is a bottom plan view of FIG. 7;

FIG. 9 is a side elevational view of FIG. 7;

FIG. 10 is an elevational view of the side opposite that shown in FIG. 9;

FIG. 11 is an end elevational view of FIG. 7; and

FIG. 12 is an elevational view of the end opposite that shown in FIG. 11.
